UNITED STATES PATENT OFFICE.

JOHN PENROD AND ROBERT D. THOMPSON, OF OKMULGEE, OKLAHOMA.

PUMPING EQUIPMENT.

Application filed April 29, 1924. Serial No. 709,746.

This invention relates to plungers especially adapted for use in well pumps and particularly the invention resides in a fluid pressure actuated means for maintaining a substantially fluid tight joint between the plunger and the working barrel.

Briefly stated, an important object of this invention is to provide novel means whereby the weight and the pressure of a column of fluid in a well tubing may be effectively utilized to establish and maintain a fluid tight joint between the lower portion of a plunger and the adjacent portion of the working barrel.

15 A further object of the invention is to provide a sealing ring having reliable means to combat the sand encountered so that the sand is prevented from cutting the parts and possibly causing the same to stick.

20 A further and equally important object of this invention is to provide a fluid sealing means which may be employed in connection with standard equipment without elaborately altering the construction of the 25 same and without a substantial expense.

Other objects and advantages will be apparent during the course of the following description.

In the accompanying drawings forming a 30 part of this application, and in which like numerals are employed to designate like parts throughout the same,

Figure 1 is a vertical sectional view illustrating a plunger equipped with the improved sectional ring, the plunger being on its down stroke.

Figure 2 is a detail sectional view illustrating the plunger on its up-stroke.

Figure 3 is a side elevation of the improved fluid pressure actuated ring, the parts being in the position they occupy on the up-stroke of the plunger.

Figure 4 is a side elevation of the fluid pressure expanded ring, the parts being in the position they occupy on the down-stroke of the plunger.

Figure 5 is an end elevation of the fluid pressure actuated ring.

Figure 6 is a horizontal sectional view 50 taken on line 6-6 of Figure 2.

Figure 7 is a horizontal sectional view taken on line 7-7 of Figure 4.

Figure 8 is a fragmentary side elevation 55 of a closed valve cage for receiving the lower traveling valve, the view illustrating a plu-

rality of recesses or slots for the discharge of sand which may collect.

Figure 9 is an end elevation of the closed valve cage illustrated in Figure 8.

In the drawings wherein for the purpose of illustration is shown a preferred embodiment of the invention, the numeral 5 designates a tubing, to the lower end of which is connected a bushing 6. Figure 1 plainly illustrates that a shell 7 is threaded onto the bushing and carries a second bushing 8. A working barrel 9 is threaded onto a boss 10 formed on the upper side of the bushing 8 and a standing valve 11 is threaded onto a reduced extension on the upper end of the boss 10. It is thus seen that the standing valve 11 is more or less permanently located in the lower portion of the working barrel and the ball or movable element of the standing valve is elevated on the up-stroke of the 70 plunger 14 to admit a quantity of fluid to the working barrel.

The invention forming the subject matter of this application resides partly in the means for providing a fluid tight or a substantially fluid tight joint between the plunger and the working barrel and to compensate for wear.

The plunger 14 has a ground fit in the working barrel, and is provided at its lower end with an internal shoulder 16, into which a connecting member 17, is threaded. The lower end of the connecting member 17 is threaded into an internal shoulder 18 on the upper portion of a closed traveling valve cage 19. The traveling valve cage 19 carries the spherical valve 20, which is unseated on the down-stroke of the plunger to admit a quantity of fluid.

It will be seen with reference to Figures 1 and 2 that the plunger 14 and the lower valve cage 19 are arranged in spaced relation and cooperate with the connecting member 17 in the formation of an annular recess for the reception of an elastic tubular body or sleeve 100 22.

The tubular elastic body 22 may be composed of rubber, rawhide or other material found suitable for the purpose, and the ends of the tubular elastic body 22 may be provided with internal enlargements 24 confined between the shoulders 16 and 18 and shoulders adjacent the ends of the member 17. By firmly locking the ends of the elastic tubular member 22 between the shoulders 110 112

on the tubular member 17 and the shoulders 16 and 18, a fluid tight joint is provided, and the shape of the tubular member 22 is maintained for a long period, notwithstanding the fact that it is elastic and is therefore capable of yielding.

As illustrated in Figure 1, the upper portion of the plunger 14 is provided with a diagonally extended opening 25 to admit a quantity of fluid from above, and the fluid thus admitted to the plunger is allowed to act on the elastic member 22 through a plurality of ports 30 in the connecting member 17.

15 When the plunger is on its up-stroke, as indicated in Figure 2, the pressure of the column of fluid in the tubing 5 will be partially exerted against the elastic tubular member 22, due to the presence of the ports 20 25 and 30, and when the member 22 is expanded, a sectional ring, consisting of sections 32 and 33, will be forced outwardly into fluid contact, or substantially fluid tight contact, with the working barrel 9.

25 However, on the down stroke of the plunger the weight of the column of fluid is supported by the standing valve, and a liquid tight connection between the plunger and the standing valve is not necessary. With 30 this in mind, attention is directed to the fact that the fluid just admitted to the working barrel is passing upwardly through the connecting member 17, and the pressure is insufficient to force the elastic member 22 outwardly. Therefore, the sectional ring is not forced outwardly with any great pressure, and the plunger may freely descend.

The opposed ends of the plunger 14 and the closed valve housing 19 are formed with 40 annular extensions 34 and 35 for the reception of annular extensions or rims 36 on the ends of the sections 32 and 33. The annular attaching portions 36 are confined within the extensions 34 and 35, and consequently the 45 sections are held in place during the insertion or withdrawal of the plunger. However, it is important to note that the sections 32 and 33 may partake of a limited longitudinal movement with relation to the elastic member 22 and other associated parts.

50 As previously stated, Figure 3 illustrates the position the fluid pressure actuated expandible ring occupies during the up-stroke of the plunger, and it will be seen that the section 32 is slightly longer than the section 33 and is provided at its side edges with extensions or lugs 44 which interlock with extensions 45 on the section 33. The sections 32 and 33 are capable of longitudinal movement with relation to each other, and on the up-stroke of the plunger the lower ends of the extensions 45 are flatly in contact with the upper ends of the extensions 44 to provide a multiplicity of spaced fluid tight 60 joints to positively prevent the leakage of

fluid between the sections. More specifically, fluid cannot work its way between the opposed longitudinal edges of the sections 32 and 33 on the up-stroke of the plunger, as the multiplicity of fluid tight joints arranged at spaced points positively prevent this.

70 On the other hand, when the plunger is moving downwardly, this fluid tight joint between the sections 32 and 33 is not necessary, and consequently only the upper end 75 of the lower extension 45 is flatly engaged with the lower end of the upper section 44. It is thus seen that only a single contact point between the extensions is provided on the down stroke of the plunger.

80 The specific construction of the sections 32 and 33 permits the same to move longitudinally with respect to each other, so that if any sand is present in the fluid, it cannot collect between and about the sections 85 and interfere with the operation of the same. Herein lies the important advantage of providing a means whereby one section is moved longitudinally with respect to the other section during the reciprocation of the plunger. 90 In summarizing this feature of the invention it will be seen that on the up-stroke of the plunger the section 33 is dragged upwardly by the section 32. On the down stroke of the plunger, the section 33 is dragged downwardly by the section 32, and in this manner the parts are maintained free of sand and consequently the plunger is not likely to stick.

95 It is also important to note that the extensions 36 define shoulders on the ends of the sections 32 and 33. The endwise movement of the section 32 is limited by the shoulders as the same contact with the extensions 34 and 35. The endwise movement of the section 33 is, in turn, limited by the interlocking members 44 and 45. The shoulders on the section 33 do not at any time contact with the annular extensions 34 and 35 as the section 33 is slightly shorter than the section 32. The annular extensions 34 and 35 are 100 as illustrated in Figures 8 and 9 formed with a plurality of recesses 48 for the discharge of sand which would otherwise lodge between the extensions 34 and 35 and the ends of the sections 32 and 33 and thereby interfere with the expansion of the ring.

105 However, a substantial quantity of sand cannot work its way into the barrel because the upper end of the barrel is provided with a sand scraping mechanism 60, which may 110 be of the type illustrated in our several prior patents. This sand scraping mechanism effectively prevents the settling sand from working its way to the expandible ring, and the sand which is arrested by the scraping mechanism 60 is directed into a trap formed between the barrel 9 and the shell 7. If desired, suitable means may be provided to return the sand in the trap to the well.

115 Figures 1 and 2 also plainly illustrate that 130

the ports 30 in the connecting member 17 are inclined downwardly and inwardly from the periphery of the member 17 to provide for the discharge of sand which may work its way into the space between the elastic member 22 and the connecting member.

Figures 3, 4, 5 and 7 plainly illustrate that transversely curved leaves 60' of elongated formation are arranged within the expansible 10 ring in overlapping relation with the longitudinal edges of the same so that the elastic member 22 cannot be forced between the said longitudinal edges under pressure of the column of fluid above. The transversely 15 curved leaves 60' may extend for the full length of the sections 32 and are secured to the same by welding or suitable fastening devices or by any other means found desirable. Figure 7 also illustrates that the inner 20 sides of the sections 32 and 33 are rabbeted for the reception of the transversely curved leaves 60', and in this manner the inner surfaces of the leaves 60' are flush with the inner surfaces of the sections 32 and 33.

If desired, the lift of the lower traveling 25 valve 20 may be slightly less than the lift of the upper traveling valve 65, so that the lower traveling valve will seat slightly before the upper traveling valve. Therefore, 30 when the lower traveling valve seats first the pressure of the column of fluid above will act on the inner side of the tubular elastic member 22 and press the ring into engagement with the working barrel. When 35 the upper traveling valve finally seats a quantity of fluid under pressure will be trapped in the plunger and will act against the expansible member 22 during the entire upstroke of the plunger.

Figure 1 illustrates an important feature 40 of the invention, wherein it is shown that the shell 7 is threaded onto the outer side of the bushing 8 and the working barrel is internally threaded for threaded engagement 45 with the outer side of the bushing 10. The annular extension on the upper end of the bushing 10 is externally threaded for engagement with the internal threads on the standing valve cage 11, and thus the standing 50 valve is securely supported within the working barrel. It will be seen that by forming the threads on the bushing 8 for the connection of the shell, the working barrel and the standing valve on the outer side of 55 the bushing the labor required in the manufacture of the bushing is substantially decreased.

Figure 1 also illustrates that the working 60 barrel, which is usually of cast iron, is provided at its lower portion with a steel tip or attaching portion 70, substantially thicker than the working barrel, but of the same internal diameter as the external diameter of the working barrel.

It is occasionally necessary to remove the

working barrel from the bushing or boss 10, and in that case a wrench may be applied directly to the tip 70. If the wrench is applied to the working barrel it is likely to crush the working barrel, as the working 70 barrel is usually of cast iron. However when the working barrel becomes unfit for use it is unthreaded from the tip 70, and if the working barrel is crushed, no harm is done and the tip 70 may be employed in connection with a new working barrel.

The lower portion of the bushing 8 is internally threaded for the reception of a gas anchor and is externally threaded for connection with a perforated inlet pipe.

We claim:—

1. In a pumping mechanism, the combination with a plunger, of an expansible sealing ring associated with the plunger, valves adjacent the ends of said plunger, and means whereby the valve at one end of said plunger may close prior to the closing of the valve at the opposite end of the plunger.

2. A plunger for use in wells comprising a body, an expansible ring mounted on the body and consisting of separate sections having the opposed edges thereof provided with spaced loosely interfitting lugs establishing a driving connection between the sections and permitting one section to partake of a limited longitudinal movement with respect to the other section.

3. A plunger for use in wells comprising a body, an expansible ring mounted on the body and consisting of separate sections having the opposed edges thereof provided with spaced loosely interfitting lugs establishing a driving connection between the sections and permitting one section to partake of a limited longitudinal movement with respect to the other section, an elastic ring within the expansible ring, a valve at the upper portion of the body, a second valve at the lower portion of the body, and means whereby the lower valve may close prior to the closing of the upper valve whereby the pressure of the fluid above the body is exerted on the elastic ring subsequent to the closing of the lower valve.

4. A plunger for use in wells comprising a body, an expansible ring mounted on the body and consisting of separate sections having the opposed edges thereof provided with spaced loosely interfitting lugs establishing a driving connection between the sections and permitting one section to partake of a limited longitudinal movement with respect to the other section, an elastic ring within the expansible ring, a valve at the upper portion of the body, a second valve at the lower portion of the body, means whereby the lower valve may close prior to the closing of the upper valve whereby the pressure of the fluid above the body is exerted on the elastic ring subsequent to the closing of the

lower valve, and transversely curved leaves overlapping said lugs.

5. A plunger for use in wells comprising a body, a connecting member associated with the body, a lower traveling valve cage supported by said connecting member, an elastic ring mounted on said connecting member and having end portions substantially increased in thickness, said connecting member, said body and said lower traveling valve cage being provided with shoulders engaging opposite sides of the thickened end portions of said elastic ring to securely hold the elastic ring in place, and an expansible ring surrounding said elastic ring.

6. A plunger for use in wells comprising a body having spaced extensions, an expansible sectional ring having its ends provided with extensions fitting within said first-named extensions, said first-named extensions being provided with a plurality of recesses for the passage of sand.

7. A plunger for use in oil well pumps, comprising a body, and an expansible ring associated with the body and consisting of a plurality of sections having loosely interlocked extensions permitting limited longitudinal movement of one section with relation to the other.

8. A plunger for use in oil well pumps, comprising a body, an expansible ring associated with the body and consisting of a

plurality of sections having loosely interlocked extensions permitting limited longitudinal movement of one section with relation to the other, and means whereby the movement of the ring longitudinally of said body is limited.

9. A plunger for use in wells, comprising a body, upper and lower traveling valves associated with the body, an expansible ring associated with the body and located between said valves, said ring being expansible under fluid pressure within the body, there being means whereby the lower valve may seat before the upper valve on the up stroke of the plunger.

10. A plunger for use in wells, comprising a body, a connecting member associated with the body, a lower traveling valve having connection with said connecting member, said body, said connecting member and said lower traveling valve being formed with shoulders, a tubular elastic member having its ends substantially thickened and engaged by said shoulders, an expansible ring surrounding said tubular elastic member, said ring consisting of a plurality of interlocking sections, and elongated leaves overlapping the interlocked portions of said sections to limit the outward movement of said elastic member.

JOHN PENROD.
